(57) CLAIM

The ornamental design for a vehicle rear end configuration, as shown and described.

DESCRIPTION

FIG. 1 is a rear elevational view of the vehicle rear end configuration showing my new design;

FIG. 2 is a rear elevational view thereof with the air dam/wing in a retracted position, which occurs when the vehicle is not moving; and,

FIG. 3 is a rear elevational view, similar to FIG. 2, showing the air dam/wing in an extended position, which occurs when the vehicle is moving.

1 Claim, 2 Drawing Sheets

FIG. 1

FIG. 2

FIG. 3
